UNITED STATES PATENT OFFICE.

CLAUDE R. DODGE, OF ST. GEORGE, UTAH.

SAD-IRON HOLDER.

1,110,190.

Specification of Letters Patent.

Patented Sept. 8, 1914.

Application filed July 25, 1913. Serial No. 781,184.

To all whom it may concern:

Be it known that I, CLAUDE R. DODGE, a citizen of the United States, residing at St. George, in the county of Washington and State of Utah, have invented new and useful Improvements, in Sad-Iron Holders, of which the following is a specification.

The invention relates to hangers, and more particularly to the class of devices for holding electric sad irons.

The primary object of the invention is the provision of a device of this character wherein a sad iron of the electrically heated type may be conveniently held while being heated or when not in use, the hanger for the iron being readily foldable so that the ironing board on which the same is attached can be stored in the least possible space when not in use without requiring the detachment of the device therefrom.

Another object of the invention is the provision of a device of this character wherein the hanger for the sad iron is swingingly connected to a clamp which can be readily fastened to a table, ironing board or other support, the hanger being swingingly supported by the clamp so that it may be folded when not in use and when in use can be locked against folding movement.

A further object of the invention is the provision of a device of this character wherein the socket plug of the electric wire on the sad iron can be held when disconnected from the iron without the accidental dropping of the plug upon the floor and also the iron will be suspended from the ironing surface of the support when not in use.

A still further object of the invention is the provision of a device of this character which is extremely simple in construction, thoroughly reliable and efficient in its purpose, readily and easily fastened on or removed from a support, and also which may be manufactured at a minimum expense.

With these and other objects in view, the invention consists in the construction, combination and arrangement of parts as will be hereinafter fully described, illustrated in the accompanying drawing, and pointed out in the claims hereunto appended.

In the drawing:—Figure 1 is a fragmentary perspective view of an ironing board showing the device mounted thereon and in upright position, the sad iron being shown by dotted lines hung upon the device. Fig. 2 is a top plan view with the hanger folded.

Fig. 3 is an edge elevation of the device with the hanger in raised position, the said hanger being shown by dotted lines in folded position. Fig. 4 is a sectional view on the line 4—4 of Fig. 3.

Similar reference characters indicate corresponding parts throughout the several views in the drawing.

Referring to the drawing by numerals, 65 the device comprises a substantially U-shaped clamp 5 in one limb of which is adjustably mounted a binding screw 6 formed with a winged end 7 and a head 8 as usual. The opposite or other limb of 70 the clamp 5 is formed with spaced vertical ears or bearings 9 between which is swingingly mounted a base block 10, the same being supported upon a pivot 11 engaged in the said ears 9 which forms the axis 75 for the base block 10 so that it may swing laterally to opposite sides of the clamp 5 for a purpose presently described. Mounted in the base block 10 and rising vertically therefrom is an upright or standard 12 80 formed with a free hook end 13 on which is adapted to be engaged an electric sad iron for suspending the same above a table top, ironing board or other support to which the clamp 5 is applied. Also engaged in the base block 10 in alinement with the upright 12 is an arm 14 which is disposed in upwardly divergent relation to the said upright 12 and is formed with a curved end 15, and between the said upright 12 and the arm 14 is adapted to be engaged the plug carried by the electric wiring connection or cord when the plug is detached from the sad iron.

Swingingly connected to the base block 95 10 is a substantially U-shaped latch bail 16 which is adapted to straddle one of the ears or bearings 9 on the clamp 5 when the upright 12 is arranged vertically so as to lock the same in such position, the said bail 16 being formed with in-turned shoulders 17 which frictionally engage the ear or bearing 9 over which the same straddles to positively lock the base block 10 against turning movement. It will be apparent that when the latch bail 16 is disengaged from the ear or bearing 9 of the clamp the said base block 10 can be swung laterally in either direction to opposite sides of the clamp for the folding of the device or the lowering of the hanger of the upright 12 and the arm 14 carried by the block against

the support to which the clamp is connected when the device is not in use. The closed end of the latch bail 16 serves as a hand hold for manipulating the same.

5 The said latch bail 16 is connected with a pivot 18 which is passed through the base block 10 between the upright 12 and arm 14 so as to engage the latter and thereby securely fasten the upright and arm in the 10 base block and also to swingingly connect the latch bail 16 to the latter.

From the foregoing it is thought that the construction and manner of operation of the device will be clearly understood, and 15 therefore a more extended explanation has been omitted.

What is claimed is:—

1. The combination with a clamp, of spaced parallel ears formed on one limb 20 of the clamp, a swinging member pivotally connected between the ears, an upright engaged in the member and having a free hook end, an arm mounted in the said member at one side of the upright, and means 25 swingingly connected to the member and engageable with one of the ears for locking the said member against swinging movement.

2. The combination with a clamp, of spaced parallel ears formed on one limb 30 of the clamp, a swinging member pivotally connected between the ears, an upright engaged in the member and having a free hook end, an arm mounted in the said member at one side of the upright, means swingingly connected to the member and engageable with one of the ears for locking the said member against swinging movement, means mounted in the clamp for securing it to a support, and a pivot for connecting 40 the first-named means to the member and also for securing the upright and arm in the said member.

3. The combination with a clamp, a member having a free hook end, an arm on the 45 member to coöperate with the same to form a substantially V-shaped fork for receiving the cord of an electric sad iron, and means for locking the member and arm in upright supporting relation on the clamp. 50

In testimony whereof I affix my signature in presence of two witnesses.

CLAUDE R. DODGE.
